(57) **CLAIM**

The ornamental design for a hair dryer holder, as shown and described.

DESCRIPTION

FIG. 1 is a top, perspective-view of a hair dryer holder;
 FIG. 2 is a top view of the hair dryer holder;
 FIG. 3 is a bottom view of the hair dryer holder;
 FIG. 4 is a right, side-view of the hair dryer holder;
 FIG. 5 is a left, side-view of the hair dryer holder;
 FIG. 6 is a front view of the hair dryer holder; and,
 FIG. 7 is a rear view of the hair dryer holder.
 The broken lines shown in the drawings represent unclaimed portions of the design and form no part thereof.
 The claimed design is shown broken away and indicates no particular length.
